UNITED STATES PATENT OFFICE.

JAMES ALBERT PERRY, OF YARMOUTH, NOVA SCOTIA, CANADA, ASSIGNOR
TO WILLIAM EDWARD PERRY, OF SAME PLACE.

EGG-BEATER.

SPECIFICATION forming part of Letters Patent No. 415,733, dated November 26, 1889.

Application filed June 17, 1889. Serial No. 314,558. (No model.)

To all whom it may concern:

Be it known that I, JAMES ALBERT PERRY, of Yarmouth, in the county of Yarmouth, Province of Nova Scotia, Dominion of Canada, have invented a certain new and useful Improvement in Egg-Beaters, of which the following is a description sufficiently full, clear, and exact to enable any person skilled in the art or science to which said invention appertains to make and use the same, reference being had to the accompanying drawings, forming part of this specification, in which—

Figure 1 is an elevation of my improved egg-beater, a portion of the body-walls being broken away to show the interior; Fig. 2, a sectional view showing the beater proper in side elevation, and Figs. 3 and 4 views illustrating certain details of construction.

Like letters and figures of reference indicate corresponding parts in the different figures of the drawings.

My invention relates to a combined egg-beater and holder; and it consists in certain novel features hereinafter fully set forth and claimed, the object being to produce a simpler, cheaper, and more effective device of this character than is now in ordinary use.

The nature and operation of the improvement will be readily understood by all conversant with such matters from the following explanation.

In the drawings, A represents the holder, and B the beater proper, considered as a whole. The holder is cylindrical in form and provided with a close-fitting cover b. The bottom d of the holder is hemispherical, the walls f thereof extending below said bottom. A rotating shaft g, provided at one end with a crank-handle h, is loosely journaled horizontally in bearings i, secured within the holder at the upper edge of its bottom d, the end of said shaft opposite its handle being screw-threaded at k. Three semicircular arms m are secured in hubs p, said hubs being preferably composed of lead or similar material. Each of said arms is provided with diagonally-arranged beater-blades q, said blades

being disposed horizontally or parallel with the shaft g when in position. Each of the hubs p is provided with a central opening to receive the shaft, its threaded end k being turned into the opening of one of said hubs, thereby securing the beater proper on the shaft.

In the use of my improvement, the parts being in position, as described, the eggs are disposed in the holder and the shaft rotated. The blades q, being arranged diagonally, are at an angle to the horizontal diameter of the spherical bottom in all positions assumed by the rotating arms, thus affording large beating-surface.

To clean the churn, the beater proper B is held stationary and the shaft turned backward until its threaded end k is turned out from the hub p, when said shaft may readily be withdrawn from the holder and the beater proper removed.

Instead of journaling the shaft in bearings i, a V-shaped smooth-surfaced lug x (see Fig. 4) may be formed on the wall of the holder, in which the threaded end of said shaft may rest, thereby preventing the egg from oozing through the opening around said shaft where it projects through the wall of the holder. A washer v on the shaft near the handle closes the opening in the holder at that end.

Having thus explained my invention, what I claim is—

The combination of a cylindrical body having a hemispherical bottom, a crank-shaft journaled in said body and provided with a screw-thread near one end, and a detachable beater on said shaft, said beater comprising hubs on said shaft, one of which is on the screw-threaded portion thereof, semicircular arms secured to said hubs, and inclined blades secured to said arms, substantially as described.

JAMES ALBERT PERRY.
